(57) **CLAIM**

The ornamental design for a ceiling grid structural member, substantially as shown and described.

DESCRIPTION

FIG. 1 is a top perspective view of the ceiling grid structural member;

FIG. 2 is a front elevation view of the ceiling grid structural member, with the rear elevation view being a mirror image of the front elevation view;

FIG. 3 is a top view of the ceiling grid structural member; FIG. 4 is a right-side view of the ceiling grid structural member, with the left-side view being a mirror image of the right-side view; and,

FIG. 5 is a bottom view of the ceiling grid structural member.

The broken lines showing a portion of the ceiling grid structural member are included for the purpose of illustrating non-claimed subject matter and form no part of the claimed design. The drawings contain a symbolic break shown with dot dashed break lines. The portion between the break lines forms no part of the claimed design.
